TELEPHONE SYSTEM

Warren W. Carpenter, Garden City, and Edgar H. Clark, Forest Hills, N. Y., assignors to Bell Telephone Laboratories, Incorporated, New York, N. Y., a corporation of New York

Application October 12, 1933, Serial No. 693,287

12 Claims. (Cl. 179—22)

This invention relates to a telephone system and particularly to a small capacity automatic telephone system.

An object of the invention is to provide improved and economically arranged systems for automatically establishing connections between telephone lines through a single cross-bar switching unit.

Heretofore systems have been provided for establishing connections between two subscribers' lines in a single cross-bar switching unit by means of links having line finders and selector branches for connecting the two lines at two cross-points of the switch. The arrangement is such that a calling line is automatically connected to the line finder branch of an idle link in response to the seizure of the line and the called line is connected to the selector branch of the idle link in response to dial pulses incoming over the calling subscriber's line. The dial pulses usually operate an auxiliary step-by-step switching means which when set operates the desired magnet that connects the called subscriber's line to the selector branch. A system of this kind is disclosed in the patent to L. R. Waller 1,567,309 of December 29, 1925.

A feature of this invention is an arrangement in a system of this kind, whereby the line relay of the calling subscriber's line is used as a lock-out means to prevent any other line from initiating a call while a connection is being established to a called line through the cross-bar switch, whereby said line relay causes the direct operation of the line magnet in the switch which identifies the calling line for a connection to the line finder branch of an idle link, and whereby said line relay also causes the idle link to be chosen and the magnet of the line finder branch to be actuated to establish a connection between this branch and the calling line.

Another feature of this invention is an arrangement whereby the line magnet identifying the desired called line for a connection at a cross-point to the selector branch of a chosen link is selected through a circuit, so arranged that each operation of a pulsing relay in the line finder branch which operates in response to impulses incoming over the calling line, actuates a succeeding line magnet and releases a preceding line magnet until the magnet of the called line is reached. This latter line magnet temporarily locks and the magnet of the selector branch of the chosen link is thereupon automatically actuated to connect this branch to the called line, whereupon the called line magnet is released.

Another feature of this invention is an arrangement in a cross-bar switch of this type in which if a calling subscriber fails to take any other action except lifting the receiver off the switchhook to connect his line with the line finder branch of an idle link within a certain period thereafter, the establishing of a connection to the called line over the selector branch of the link is prevented and whereby under such circumstances this link is released from the calling line and the calling line is then connected to a holding trunk in the switch.

This invention has been illustrated in the accompanying drawing which shows one embodiment of the invention. An ordinary cross-bar switch of the type disclosed in Patent 1,168,419 of January 18, 1916, to J. N. Reynolds may be employed and has been illustrated in diagrammatic form at S. This switch may be arranged for a number of lines 1 to 0 terminating in the switch at cross-points in contact sets arranged in a horizontal row for each line. Of these lines 1, 2, 9 and 0 only have been shown. The contact sets of these lines have access at the various cross-points to contact sets associated with links two of which have been shown at A and B respectively. The calling lines have access to the branch A1 of link A or B1 of link B and the called lines have access to the branch A2 of link A or B2 of link B. A holding trunk C has also been shown to which each line has access through a contact set in its individual row of the switch. The detail circuit arrangement individual to link A has been shown at D while the major portion of the circuits individual to link B has been omitted but may terminate at E. The circuit equipment common to both links has been shown at F. The horizontal operating magnets for connecting the lines to the links have been shown as follows: the magnet for line 1 at S1, for line 2 at S2, for line 9 at S9, and for line 0 at S0. The vertical operating magnets have been shown at 10 for branch A1, at 11 for branch A2, at 12 for branch B1, and at 13 for branch B2, while the vertical operating magnet for the holding trunk C has been shown at 14. It should be understood that the operation of one horizontal magnet followed by the operation of one vertical magnet and the release of the operated horizontal magnet causes a connection to be established between a line and a branch of an idle link or between a line and the holding trunk C in the same manner as outlined in the above mentioned patent to Reynolds.

A description will now be made of the opera-

5

10

25

30

35

40

45

50

55

tion of these circuits while establishing a connection from a calling line 1 to a called line 2, over the link A.

If the subscriber of line 1 lifts his receiver from the switchhook a connection is established through the subscriber's loop in the usual manner from ground at contacts of relay 20 over the ring conductor through the loop back over the tip conductor, contacts of relay 20 through a winding 5 of relay 21, contacts of relay 22 to battery. This causes the operation of relay 21. This relay in operating closes a locking circuit for itself and a circuit for the operation of relay 22 as follows: From battery through the other winding 10 of relay 21, an armature and front contact of this relay, armatures and back contacts of relays corresponding to relay 21 of the other lines, winding 15 of relay 22 to ground at contacts of relay 23. The operation of relays 21 and 22 closes a circuit for the operation of the magnet S1 and relay 24 20 from battery through the winding of this magnet, contacts of relay 21, contacts of relay 22, winding of relay 24, to ground at contacts of relay 25. Relay 22 also closes a circuit for the timing relay 26 from battery through the winding of this relay, contacts of relay 22 to ground. This circuit 25 also branches out through a thermostatic device 27 associated with the relay 26 to re-establish the connection between the armature and back 30 contact of relay 26 after a certain interval. The purpose of relay 26 and its thermostatic device is to disconnect the calling line from the seized branch of an idle link a certain interval after the calling subscriber has removed his receiver from the switchhook if he has taken no further 35 action towards the establishing of a connection to a desired line through the seized link. A detail description of this feature of the invention will be made hereinafter.

The operation of the magnet S1 prepares the cross-bar switch for the connection of the line 1 to the branch A1 of the link A, which it is assumed is idle. The busy or idle condition depends on whether relay 29 is operated or in normal condition. The operation of relay 24 closes 40 a circuit for the operation of relay 28 of the link A as relay 29 is not actuated. This circuit may be traced from battery at contacts of relay 24, contacts of relay 32, winding of relay 28 to ground at contacts of relay 29. If the link B had been 45 idle relay 30 would have been operated. This relay in operating would have opened the holding path for relay 28 through its armature and back contact as well as its original energizing circuit due to the subsequent operation of relay 50 55 32, thus preventing relay 28 from being maintained operating. However, as branch A is idle relay 28 is operated and closes an obvious circuit for the operation of relay 31. Relay 28 now 60 closes a locking circuit for itself and for the operation of relay 32 from battery, the other winding of relay 28 and an armature and front contact, an armature and back contact of relay 30, winding of relay 32, to ground at the contacts of relay 23. Relay 34 is also operated by the operation 65 of relay 28 from battery, winding of relay 34, an armature and back contact of relay 35, an armature and front contact of relay 28 to ground at make before break contacts of relay 36. The purpose of the operation of relay 34 will be 70 apparent hereinafter. The operation of relay 32 closes a circuit for the operation of the magnet 10 for connecting the branch A1 of link A to the calling line 1. The circuits for this magnet may be traced from battery, winding of magnet 10, an armature and front contact of relay 31

an armature and back contact of relay 25 and an armature and front contact of relay 32 to ground at contacts of relay 23. The calling subscriber's line is now connected over the tip and ring conductors and the contacts at the cross-point 41 of line 1 and branch A1 to battery and ground through the windings of pulsing relay 39. This relay in operating closes an obvious circuit for relay 40 which in turn closes an obvious circuit for relay 29. Relay 29 in operating closes a circuit for the operation of relay 20 from battery, winding of relay 20, the sleeve conductor and contacts at 41 of the cross-bar switch, contacts of relay 29 to ground at contacts of relay 43. Relay 29 in operating also closes an obvious locking circuit through the sleeve conductor for magnet 10. Relay 29 also closes a circuit for the operation of relay 25, from battery, winding of this relay, an armature and front contact of relay 31, an armature and back contact of relay 43, and an armature and front contact of relay 29 to ground. This relay in operating opens the circuit for the magnet S1 and relay 24 causing them to release and opens the original energizing circuit for magnet 10 which is held operated by the locking circuit over the sleeve conductor. A dial tone is now transmitted to the calling subscriber's telephone set from the dial tone source at 44 an armature and front contact of relay 31, condenser 45 over the ring conductor of the calling subscriber's line indicating that dialing may take place.

When the calling subscriber now dials he will on the first impulse cause the release and reoperation of the pulsing relay 39. On the release 35 of relay 39 a circuit is completed for the operation of relay 36 from battery, winding of this relay, an armature and back contact of relay 39 to ground at an armature and front contact of relay 29. Relay 36 remains operated during the pulsing due 40 to its slow to release characteristics. The operation of relay 36 closes an obvious circuit for the operation of relay 47 and this relay in turn closes an obvious circuit for the operation of relay 48. Relay 36 in operating opens the circuit for relay 45 34 thus permitting relay 35 to operate from ground at contacts of relay 32 which now hold both relays 34 and 35 operated. A circuit is also completed due to the release of relay 39 for the operation of relay 46. This circuit may be traced 50 from battery through a resistance and winding of relay 46, make-before-break contacts of relay 46, an armature and front contact of relay 31, an armature and front contact of relay 29 to ground at an armature and back contact of relay 39. When now the pulsing relay 39 is again operated at the end of the first impulse, a circuit is completed for the operation of relay 50. This circuit may be traced from battery through a resistance, winding of relay 50, an armature and front contact of relay 46 to ground at the contacts of relay 23. It should be noted now that relays 46 and 50 are locked to this ground at relay 23. The operation of relay 50 closes a circuit for magnet S1 from battery winding of this magnet, an 65 armature and front contact of relay 50, make-before-break contacts of magnet S1 and corresponding make-before-break contacts of the succeeding horizontal magnets an armature and front contact of relay 25, an armature and front contact of relay 35 to ground. Magnet S1 in operating closes a locking circuit for itself at its right hand armature and front contact to the ground at relay 35. When relay 39 is again released at the beginning of the second impulse, a 70 75

short circuit is provided for the release of relay 46 by the ground from an armature and back contact of relay 39 and an armature and front contact of relay 50. When relay 46 is released the relay 50 remains operated through the make-before-break contacts of relay 46 to the ground at relay 39. The magnet S2 is now operated from battery through the winding of this magnet, an armature and front contact of magnet S1 an armature and back contact of relay 46 to ground. Magnet S2 provides a locking circuit for itself through one of its armatures and front contact to the ground at relay 35, and opens the holding circuit for magnet S1 which is thereby released. When the pulsing relay 39 is again operated, the ground is removed from the holding circuit for relay 50 which is thereby released. If a third impulse had been transmitted the release and operation of the pulsing relay 39 would have caused the relays 46 and 50 to be operated and the succeeding magnet S3 (not shown) would have been operated, while if a fourth impulse had been received, the relays 46 and 50 would have been released and the fourth magnet would have been operated. That is, the relays 46 and 50 are therefore alternatively operated and released by the succeeding impulses.

It should also be noted that at each operation of a succeeding S magnet the immediate preceding S magnet releases due to opening of the locking circuit therefor. As only two impulses are transmitted in this case to select line 2, the final operation of the pulsing relay 39 causes the release of relay 36. Relay 36 in releasing causes the release of relays 47 and 48 after an interval as relay 47 is slow in releasing. Relay 36 in releasing also closes a circuit for the operation of relay 52 from battery, winding of this relay, an armature and front contact of relay 35, an armature and front contact of relay 28, an armature and make-before-break contacts of relay 36 to ground. The operation of relay 52 closes a circuit for the operation of relay 53 and magnet 11 from battery, winding of magnet 11, an armature and front contact of relay 31, an armature and back contact of relay 54, winding of relay 53 to ground at the armature and front contact of relay 52. The operation of magnet 11 establishes a connection from the branch A2 of link A through the contacts at 56 to the tip and ring conductors of line 2. The contacts at 56 now also close a circuit for the operation of relays 57 and 58 from battery, winding of relay 58, sleeve contacts at 56, a winding of relay 57, an armature and front contact of relay 48 to ground. Relay 57 in operating provides a locking circuit for itself and relay 58 through an armature and front contacts to ground at relay 29 independent of the ground at relay 48 which relay will presently release. Relay 58 in operating disconnects the line 2 from relay 59 to prevent this latter relay from operating when the called subscriber answers. Magnet 11 is locked through its armature and front contact, contacts at 41, an armature and front contact of relay 29 to ground at an armature and back contact of relay 43. Relay 53 in operating closes an obvious circuit for the operation of relay 60 but as relay 53 immediately thereafter releases due to the short-circuiting ground from relay 29 that holds magnet 11 operated the operation of relay 60 may then close a circuit for the operation of relay 23 from battery winding of relay 60, armature and front contact of relay 60, winding of relay 23 to ground at an armature and front contact of relay 32. The operation of relay 23 causes the re-

lease of the relays and magnet S2 held operated at this time from the ground at contacts of this relay. If relays 46 and 50 had been operated they would now be released, but due to the fact that only two impulses were transmitted they have already been released. For example, if three impulses have been transmitted they would have been operated at this time and would now release. Relays releasing at this time are 32, 28, 31, 35, 34, 25, 52, 21, 22, 26, and relay 32 in releasing causes the release of relays 23 and 60.

It should be noted that when relay 57 operated and before relay 48 released a circuit was completed for the operation of relay 62 from battery, winding of this relay, an armature and front contact of relay 57, an armature and front contact of relay 48 to ground. Relay 62 immediately locks over an armature and front contact through an armature and back contact of the ringing trip relay 63, an armature and front contact of relay 29 to ground at relay 43. At this time therefore only relays 57, 62, 39, 40, 29, 20 and 58 remain operated. The operation of relay 62 closes a circuit from a ringing source at 65, the winding of ringing relay 63, an armature and front contact of relay 62, contacts at 56, the ring conductor through the called subscriber's telephone set and back over the tip conductor, contacts at 56, an armature and front contact of relay 62 to ground, to transmit ringing current to call the subscriber of line 2. When the subscriber of line 2 answers, ringing relay 63 is operated causing the release of relay 62 and this relay in turn opens the ringing circuit and causes the operation of relay 66 from battery, winding of this relay, an armature and back contact of relay 62, an armature and front contact of relay 57 to ground at the armature and back contact of relay 48. The ringing relay 63 is then released. A conversational connection is now established from the calling subscriber on line 1 through the cross-bar switch contacts at 41, the branch A1 of link A, condensers 45 and 68, armatures and front contacts of relays 66, cross-bar switch contacts at 56, the tip and ring conductors to the subscriber of line 2. Talking battery for the calling line 1 is provided from the source through the windings of the pulsing relay 39, and talking battery for the called line is provided from the source through the windings of relays 67. When the calling subscriber releases, relays 39, 40 and 29 are released causing the release of relays 57, 66, 20 and 58 and the vertical magnets 10 and 11. The circuits are thereby returned to normal condition.

A description will now be made of the operation of these circuits to release the link A seized by the calling subscriber's line 1 when the calling subscriber removes the receiver from the hook in case he does not dial within a certain period thereafter, and how the calling subscriber's line is transferred to the holding trunk C and prevented from again seizing an idle link until after he has replaced the receiver on the switchhook.

It should be remembered that when the branch A1 of link A was seized relay 26 was operated on the operation of relay 22. If the subscriber fails to dial within a certain period the thermostatic element 27 will be sufficiently heated to move the armature of relay 26 to close its back contact. When this takes place a circuit is completed for the operation of relay 54 from battery, winding of this relay, armature and back contact of relay 26 to ground at contacts of relay 22. Relay 54 in operating closes a circuit for

the operation of relay 43 from battery, winding of this relay, contacts of relay 31, contacts of relay 54 to ground at contacts of relay 32. Relay 43 in operating causes the release of relay 25 and this relay in turn causes the operation of relay 24 and horizontal magnet S1. Relay 24 causes the operation of the vertical magnet 14 and relay 53 over a circuit from battery, winding of magnet 14, contacts of relay 54, winding of relay 53, contacts of relay 24, contacts of relay 54, to ground at contacts of relay 32. Relay 53 operates relay 60, magnet 14 closes the connection for the calling line 1 through contacts at 71 of the holding trunk and relay 72. The closing of the contacts at 71 causes the operation of relay 20 due to the operation of relay 72 and locks relays 20 and magnet 14 in operated positions. Relay 72 by providing the ground for locking magnet 14 short circuits relay 53 so as to permit the operation of relay 23 from the ground at relay 32. Returning now to relay 43 this relay in operating also opens the circuit for the magnet 10 thereby causing the release of the calling subscriber's line from the branch A1 of the link A. This causes the release of relays 39, 40 and 29. The operation of relay 23 now causes the release of certain other relays remaining actuated at this time such as 32, 28, 31, 34, 22, 24, 21, 26, 54, 23 and 60 and magnet S1. The calling subscriber of line 1 is now therefore connected to trunk C and prevented from seizing an idle link to extend a connection through the switch and until after he has replaced the receiver on the switchhook when relay 72 is released causing the release of relay 20 and magnet 14. He may then again remove the receiver to initiate a call in the usual manner as heretofore described.

What is claimed is:

1. In a telephone system, a cross-bar switch, lines terminating in said switch, links having two branches terminating in said switch, a line relay for each line operative on the seizure of a line by a calling subscriber, a line magnet for each line, a magnet for each branch, means responsive to the actuation of the line relay of a calling line for preventing the operation of any other line relay in case any other subscriber seizes his line, means responsive to the actuation of said line relay for directly operating the associated line magnet, means responsive to the actuation of said line relay for selecting an idle link and for actuating the magnet for one branch of said link to connect the calling line to said branch, and means for thereafter connecting any one of the other lines to the other branch of said link including the operation of the line magnet of the other line connected and the magnet of the other branch connected to the calling line.

2. In a telephone system, a cross-bar switch, lines terminating in said switch, links having two branches terminating in said switch, a line relay for each line operative on the seizure of a line by a calling subscriber, a line magnet for each line, a magnet for each branch, means responsive to the actuation of the line relay of a calling line for preventing the operation of any other line relay in case any other subscriber seizes his line, means responsive to the actuation of said line relay for directly operating the associated line magnet, means responsive to the actuation of said line relay for selecting an idle link and for actuating the magnet for one branch of said link to connect the calling line to said branch, a pulsing relay in said branch, means responsive to the

connection of said branch to the calling line for actuating said pulsing relay, means responsive to the actuation of said pulsing relay for releasing the calling line magnet and for holding said actuated branch magnet operated.

3. In a telephone system, a cross-bar switch, lines terminating in said switch, links having two branches terminating in said switch, a line relay for each line operative on the seizure of a line by its calling subscriber, a line magnet for each line, a magnet for each branch, means responsive to the actuation of a line relay for preventing the operation of any other line relay in case any other subscriber seizes his line.

4. In a telephone system, a cross-bar switch, lines terminating in said switch, links having two branches normally disconnected and terminating in said switch, a line magnet for each line, a magnet for each branch, means for selecting an idle link and for connecting a calling line to one branch of said link including the operation of the line magnet for the calling line and the operation of the magnet for said branch, means controlled over said connected branch for actuating and releasing in succession the line magnets until the line magnet of a desired called line is reached, means for thereafter connecting the other branch of said link to said called line including the temporary maintaining of the line magnet of the called line operated and the permanent operation of the magnet of said other branch, and means thereafter operated for inductively connecting said branches together.

5. In a telephone system, a cross-bar switch, lines terminating in said switch, links terminating in said switch, means for establishing a connection from any calling line to any other line through an idle link responsive to two separate succeeding actions on the part of the calling subscriber, and means operative to prevent a connection from being established if the second action is not taken within a certain interval after the first action.

6. In a telephone system, a cross-bar switch, lines terminating in said switch, links terminating in said switch, means responsive to the subscriber of a calling line removing his receiver from the switchhook for connecting his line to an idle link, means responsive to impulses received over the calling line for connecting said idle link to any other line, means for releasing the calling line from said idle link a certain period after the removal of the receiver from the switchhook if the subscriber takes no further action towards the establishing of a connection within this period.

7. In a telephone system, a cross-bar switch, lines terminating in said switch, links terminating in said switch, means for seizing an idle link from any calling line, means for connecting any other line to said seized link, means for releasing the seized link from a calling line if no action is taken towards the establishing of a connection to any other line within a certain period after the seizure of the link, and means for thereafter preventing the reseizure of an idle link by said calling line as long as the calling subscriber's receiver remains off the hook.

8. In a telephone system, a cross-bar switch, lines terminating in said switch, links terminating in said switch, means for establishing a connection from any calling line to any other line over an idle link operative by the calling subscriber removing his receiver from the switchhook followed by impulses transmitted over the calling line and means operative to prevent said connection from being completed if impulses are not

received within a certain period after the removal of the receiver from the switchhook.

9. In a telephone system, a cross-bar switch, lines terminating in said switch, links terminating in said switch, means for establishing a connection from any calling line to any other line over an idle link operative by the calling subscriber removing his receiver from the switchhook followed by impulses transmitted over the calling line, a special link terminating in said switch, means operative to prevent said connection from being completed if impulses are not received within a certain period after the receiver is removed from the switchhook, and means thereafter operative for connecting the calling line to said special link and maintaining this connection until the calling subscriber replaces his receiver on the switchhook.

10. In a telephone system, a cross-bar switch, lines terminating in said switch, links terminating in said switch, means for establishing a connection from any calling line to any other line over an idle link operative by the calling subscriber removing his receiver from the switchhook followed by impulses transmitted over the calling line, a special link terminating in said switch, means for releasing the calling line from said idle link a certain period after the removal of the receiver if impulses are not received within this period, means thereafter operative for connecting the calling line to said special link, and means for disconnecting the calling line from said special link when the calling subscriber replaces his receiver on the switchhook.

11. In a telephone system, a cross-bar switch, lines terminating in said switch and arranged in rows, links terminating in said switch having two branches and arranged in rows intersecting the line rows, line connecting magnets one for each line, link connecting magnets one for each branch,

a pulsing relay means associated with one branch of each link, means responsive to the seizure of a calling line for selecting an idle link for connecting the calling line with the branch of said idle link associated with the pulsing relay means at the intersecting point of the corresponding row of said calling lines and said branch and including the operation and release of the connecting magnet of said calling line and the operation of the connecting magnet of said branch, means responsive to the actuation of the pulsing relay means of the connected branch by impulses received over the calling line for actuating and releasing in succession the line connecting magnets until the magnet of the desired line is actuated and for thereafter actuating the connecting magnet of the other branch of the seized link to connect said branch with the called line at the intersecting point of the corresponding rows of said called line and said other branch, means thereafter operative for signaling the subscribers of said called line, and means operatively responsive to the called subscriber answering the call for connecting the two branches of the seized link together to establish a conversational connection between the calling and the called subscribers' lines.

12. In a telephone system a cross-bar switch, lines terminating in said switch, links having two branches terminating in said switch, a line relay for each line operated on the seizure of a line by its calling subscriber, a line magnet for each line, a magnet for each branch, a relay, means for operating said relay in response to the operation of any one of said line relays, and means responsive to the operation of said relay for preventing the operation of any other line relay in case any other subscriber seizes his line.
